APPARATUS FOR PRODUCTION OF LOW
BOILING POINT HYDROCARBONS

Joseph Wilson Trotter, Toronto, Ontario, Canada

Application May 11, 1937, Serial No. 141,961

9 Claims. (Cl. 196—106)

The principal objects of the invention are to produce a gasoline, ether or other liquid hydro-carbon of high quality both in respect to purity and octane rating, which will produce extraordinarily high results in power values when used in internal combustion engines.

A further and important object is to produce a hydrogenated product free from sulphur and other agents which will deleteriously affect metal parts with which it may come in contact when in use.

A still further object is to devise a process which may be effectively controlled to eliminate losses and to produce the desired results in an economical manner.

The principal features of the invention consist in the novel steps of treatment of hydro-carbon oils of the paraffin series of approximately 45° to 47° Baumé in the presence of superheated steam whereby increasing temperatures and decreasing pressures are applied in non-corrosively lined apparatus, and in the provision of an arrangement of apparatus to enable the effective treatment of the different boiling points in the oil constituent step by step and from which the heavier products can be removed in the various purifiers and separators provided, as will appear from the following detailed description of the apparatus and the successive steps of treatment of the hydro-carbons therein.

In the accompanying drawings,

Figure 1 is a diagrammatic plan of the arrangement of the various units comprising a complete plant for exercising the improved process of producing various products from hydro-carbon oils.

Figure 2 is an enlarged plan view showing the arrangement of the feed tank receiving its supply from the oil preheaters and the accumulator and high pressure reaction chambers connected therewith.

Figure 3 is a longitudinal sectional elevation of one of the reaction chambers.

Figure 4 is a longitudinal part sectional elevation of one of the vaporizers shown connected to the reaction chambers.

Figure 5 is a longitudinal part sectional elevation of one of the converters.

Figure 6 is a plan section of the converter on the line 6—6 of Figure 5.

Figure 7 is an enlarged diagrammatic plan of the heater of the converter.

Figure 8 is a longitudinal sectional view of one of the digesters.

Figure 9 is a cross sectional view through the digester on the line 9—9 of Figure 8.

Figure 10 is a longitudinal part sectional elevation of one of the purifiers.

5 Figure 11 is an enlarged diagrammatic plan of the battery of converters and digesters connected with the vaporizers.

Referring to the drawings, a storage tank 1 of suitable capacity for containing a supply of topped crude hydro-carbon is arranged in a desirable location. The hydro-carbon is conducted from the tank 1 through a valve-controlled pipe 2 to a battery of high pressure pumps 3 which feed at a pressure up to 1000 lbs. per square inch to an

10 15 accumulator 4.

A reservoir 6 is piped to connect with the pipe 2 leading to the pumps 3 and is also connected by a pipe 2' to the lead from the storage tank 1, both pipes being controlled by suitable valves.

20 25 20 A battery of preferably five steam boilers 7 of approximately 500 H. P. each is provided and the steam generated therein to approximately 250 lbs. is conducted through a valve-controlled pipe 8 to a battery of preferably four steam superheaters 9 which raise the steam to a temperature of approximately 1200° F. Steam may be conducted from the superheaters through a valve-controlled pipe 10 to a preparatory tank 11 which receives a supply of residue oils from other parts

30 35 30 of the system as will hereinafter appear. The oil is conducted from the tank 11 through the valve-controlled pipe 12 to the pipe 2 at the intake side of the pumps 3 and is mixed with the topped crude hydro-carbons and fed by said pumps into the accumulator 4 in a preheated condition.

36 40 36 The hydro-carbons pumped to the accumulator 4 are conducted therefrom by pipe 13 to one or more of a battery of preheater furnaces 14 in which it is heated to a temperature of approximately 750° F. and from the furnaces it is conducted by a valved pipe 15 to the feed tank 16

45 50 45 where it is unified before passing on through pipe 17 to an accumulator 18 from which it flows through valve-controlled branches to the high pressure molecular reaction tanks 19 which are arranged in a battery within an enclosed heat-retaining chamber 20 and are adapted to break up the mass by bruising and separating the molecules.

55 59 55 The vapours at a pressure and temperature respectively of approximately 1000 lbs. and 750° F., are fed into one or more of the reaction tanks 19, as may be required, which are approximately 36" diameter by 35 feet in length, through trans-

verse conduits 21 leading to a centralized perforated drum 22 (Fig. 3) which breaks up the flow, dispersing same throughout the tank and the mixture flows the length of the tank, passing through and being further separated and broken up by its passage through perforated plates 22' arranged at intervals throughout its length. The discharge from each tank 19 enters a pipe 23, arranged in the longitudinal centre thereof, through a perforated strainer 24. The tanks and pipes are preferably formed of a nickel steel alloy.

The pipe 23 conducts the vapour, which has been held in passage through the tanks 19 for a period of approximately fifteen minutes at a 15 temperature sustained by the walls of the chamber 20 at a pressure of approximately 1000 lbs. per square inch, to a tank 24' arranged transversely of the battery of reaction tanks 19 and in which the product is unified. From the tank 20 25 it is conducted through valved pipes 24'' to a group of vertical vaporizers 25 (Figure 4) into which it is sprayed through a perforated coil 25' into a body of oil, which is fed to the vaporizers from a feed tank 25*, at a temperature of about 750° F., thereby imparting heat to the body of oil which is carried to a series of purifiers as hereinafter described.

The vapours rising in the vaporizers 25, which are approximately 8 feet in diameter and 60 feet 30 high, are conducted to a battery of twelve converters 26, shown in detail in Figure 12, by a conduit 27, which is connected by valved leads 27' to each converter.

The vapor enters each converter through the 35 tubular column 28, (see the detail Figure 5) which discharges from the lower end against an electrically heated hot plate 29 (Fig. 7) arranged immediately below a perforated plate arranged in the end of the column (Fig. 6). Screens of 40 a decreasing mesh are arranged between the several sections of the column 28. A perforated tube ring 30 is arranged below a baffle 31 in each converter to act as a blow-out to clean out the bottom of the converters through a valved clean-out 32, steam being conducted thereto from the steam line S through valved branch pipes s.

The vapours are discharged from each converter through a perforated rose 33 to the outlet 34. The discharge of the vapours against the 50 hot plates in the converters raises the temperature, which has been reduced in the vaporizers, to approximately 1000° F. at a pressure of about 250 lbs., and the resultant reaction is to produce in the converters a vapour which will produce a gasoline of from 60° to 68° Baumé in accordance with the number of converters it is passed through. Gasoline of approximately 60° Baumé and 70 octane may be produced by passing the vapours through converters a to d, 64° Baumé by passing through eight converters a to i and 55 68° Baumé by passing through the twelve converters a to m.

The battery of converters is preferably arranged in groups of six, a to f, each converter being approximately 6 feet in diameter and 60 feet high, and the outlets 34 are coupled to a common conduit A.

It will be seen that vapour can be fed directly 70 to each of the converters of this group of six and taken off by the conduit A, but suitably valved by-pass pipes g are arranged so that the discharge from the first group of three converters a to c or any additional number may be taken 75

in series through the remainder of said group of six.

The discharge from the first group of six is conducted through conduit A to the inlet of the end converter h of the second group h to m and the discharge from h and the succeeding tanks of the group may be carried in series by the valved by-pass pipes n or the discharge may be conducted by a common conduit B to a conduit C, which is connected to the inlets 35' of the battery of digesters 35, which are approximately 4 feet in diameter and 60 feet high.

The vapour flows into each digester through a vertical column 36, see Figure 8, and is discharged from the lower end of the column against an electric hot plate 36* as shown in Figure 8, and steam at about 1000° F. is injected through the coil 37 fed thereto through the conduit 37' leading from the steam line S. The steam striking the hot plate, being convergently directed by the baffle 39 causes a separation of the hydrogen which mixes with the vaporized oil which is maintained at a temperature of about 1000° F. and a pressure of 250 lbs. Perforated screen 39* are arranged in spaced relation throughout the height of the tank to effect a thorough unification of the oil and hydrogen molecules and a thorough saturation of the hydro-carbons.

A perforated rose 40 is arranged at the inner end of the outlet conduit 41 of each digester. A perforated coil 38 is arranged in each digester and is connected by a conduit 38' to a high pressure air line to enable the cleaning of the digesters.

Valved by-pass conduits 41' connect the outlets of each digester with the inlets 35' to enable the vapours being passed in series through the digesters or such vapours may be carried to the digesters in multiple and a common conduit 41* is connected to all outlets. Petroleum ether may be produced in passing the vapours through the entire battery of converters and digesters at predetermined temperatures and pressures and the regulation of time treatment by the control of the various valves in the system.

The outlet conduit 41* from the digesters conveys the produced vapour to a battery of rest chambers 42 which are in the form of vertical cylinders approximately 8 feet in diameter and 60 feet high, in which the vapour may be held at a temperature of approximately 1000° F. and a pressure of about 250 lbs. for a period of about thirty seconds more or less in accordance with the particular characteristic of the product desired. From the stills 42 the vapours are conducted to an accumulator header 43, which is about 3 feet in diameter and 25 feet long and which overcomes any surge.

The outlet 44 from the header 43 is connected by pipe 45 with the superheated-steam line S.

An oil separator 46 is arranged in the outlet 44 and said outlet leads through a conduit 47 in the form of a vertical loop arranged in an expansion tower 48, which is externally heat insulated to maintain temperatures. This loop extends from the top of the tower to a point adjacent to the bottom where it discharges its vapours against a heater plate 49. The tower 48 which is about 12 feet diameter and 175 feet high is provided with spaced screens 50 ranging from about 40 mesh at the bottom to 80 mesh at the top, which further ensures the thorough admixture and treatment of the hydro-carbon gases. These screens are of silver wire which

assist in raising the hydrogen content of the hydrocarbon vapours.

Any oil condensed in the accumulator 43, the oil separator 46 or the tower 48 is conducted by a pipe line 51 to the preparatory tank 11.

The oil heated in the vaporizers 25 and any condensates from the converters 26 and digesters 35 is conducted to a battery of purifiers 52 which are here shown in the form of a series of tanks of about 8 feet diameter and gradually decreasing height from 80 feet to 50 feet. The oil is fed into perforated tube rings 53 arranged near the bottom thereof which project the oil upwardly in fine jets into a body of distilled water, supplied by a pump 56 connected with the supply tank 57. Any suitable means may be provided for maintaining the water at a desired level in each purifier. The oil rising to the top of each of the purifiers is conducted from the top of one purifier to the bottom of the adjacent one, and in its passage through the series is divested of its sulphur and other objectionable constituents.

The final oil product of the purifiers is fed into a perforated tubular conduit 58 extending longitudinally of the preparatory tank 11 approximately 10 feet diameter and 40 feet long to treat the crude oil to bring it to the desired gravity.

A pipe 59 leads from the tank 11 to a blow-down tank 60 and connections 61 lead from the bottom of each of the purifiers to said blow-down.

The vapour rising from the tower 48 is carried through pipe 62 to the vapour condenser 63 of any suitable form.

The vapour or partly condensed produce is then directed from the condenser 63 to the surface condenser 66 or to the water condenser 67 which is arranged in a suitable by-pass circuit.

A vacuum pump 68 conducts the condensate to the settling tank 69.

Electric energy from a suitable source is supplied for motorized valves which are used throughout and for the heaters and lighting etc.

It is an important feature of this process that all the tanks, such as the accumulators, pre-heaters, preparatory chamber, reaction tanks, vaporizers, converters, digesters, stills, etc. (and all connecting piping) are made of such dimensions as to carry the high pressures and temperatures required and all such tanks are preferably monel metal lined which prevents corrosion and assists in the hydrogenation of the petroleum which is treated throughout in the presence of steam.

What I claim as my invention is:

1. An apparatus for treating hydro-carbons comprising in combination high pressure pumping means, means for introducing hydro-carbons in predetermined proportions to said pumping means, heating coils receiving the discharge from said pumping means, means for heating said coils, a series of reaction tanks, conduit means receiving the heated product from said heating coils and connected in multiple with one end of each of said reaction tanks to supply said product thereto, means for selectively and variably controlling the flow through said reaction tanks to retain the product under pressure for a predetermined time, vaporizers, means maintaining liquid bodies of hydro-carbon in said vaporizers, means connected with said reaction tanks for receiving and conducting the said heated product therefrom to said vaporizers, means in said vaporizers connected with the latter means for receiving the said product therefrom and projecting the same upwardly

through the bodies of liquid hydro-carbon in the vaporizers, conduit means connected with the upper end of said vaporizers for receiving and conducting the resultant vapour product therefrom, a battery of converters, means for variably directing said resultant vapour from said latter conduit means to said converters in accordance with the characteristics required of the final product, heaters in said converters, and means for condensing the resultant vapour product.

5 2. An apparatus as claimed in claim 1 in which the converters comprise tanks with heaters therein to first heat the incoming vapours from the vaporizers and being provided with means for feeding steam into the flow of heated vapours as they are released from said heaters into the tanks.

10 3. An apparatus as claimed in claim 1 in which the vapour from the vaporizers is fed through a common conduit and individual valved branches to each converter, and each converter is provided with a valved outlet connected to a common conduit, and valved by-pass conduits are arranged between said individual inlets and outlets to conduct the vapours from the vaporizers in series through the converters or in multiple in accordance with the characteristics required of the product to be produced.

15 4. An apparatus as claimed in claim 1 in which each of said converters is formed with a downwardly extending inlet, a hot plate arranged opposite to the discharge end of the inlet, means for convergently distributing steam into the vapours discharged from said inlet, an outlet, and valved means for controlling the flow of vapours to the inlets and from said outlets.

20 5. An apparatus as claimed in claim 1 in which digesters are provided with downwardly extending inlets and conduit means to receive the vapours emanating from said converters and conduct same to said downwardly extending inlets, a series of screens being disposed in surrounding relation to the inlet, means being provided for raising the temperature of the incoming vapours, and means for introducing steam into the digesters.

25 6. An apparatus as claimed in claim 1 having digesters connected with and receiving the vapours from said converters, valved conduit means for selectively directing the vapours through said digesters in series or in multiple, rest chambers receiving the vapours from the digesters, an expansion tower, conduit means directing the vapours from said rest chambers into the lower end of said tower, said tower having a plurality of screens disposed in the path of flow of the vapours, a condenser connected with the top of said expansion tower, and means for separating the condensates.

30 7. An apparatus as claimed in claim 1 having digesters connected with and receiving the vapours from said converters, rest chambers having valved inlets and outlets, means for variably connecting said digesters to said valved inlets, a header tank, conduits connecting said rest chambers with said header tank, means for adding steam to the vapours at the header tank, an expansion tower, a conduit connecting the header with the expansion tower, an oil separator in said latter conduit, and condensers connected to the expansion tower.

35 8. An apparatus as claimed in claim 1 in which the reaction tanks comprise a multiple of tanks connected in parallel in the flow circuit and having valved inlets and outlets at the respective

ends, said inlets and outlets being screened, screens interposed in the length thereof, a tank arranged transversely to the aforesaid tanks and connected to the several outlets, and valved outlets from the latter tank respectively connected to said vaporizers.

9. In an apparatus as claimed in claim 1, a series of purifiers connected with said vaporizers, each of said purifiers containing a body of distilled water and having means in the bottom for

spraying fluid hydro-carbon upwardly therein, means for supplying fluid hydro-carbon to said latter means, means for conducting the liquid hydrocarbon in series from the top of each purifier to the spraying means in the bottom of the next, a preparatory tank connected to the final discharge of said purifiers, and means for feeding the contents from said preparatory tank to the inlet of said pumping means.

JOSEPH WILSON TROTTER.
